CHAIR

Allan H. Crawford, Amsterdam, N.Y., assignor to Mohasco Industries, Inc., Amsterdam, N.Y., a corporation of New York

Filed Oct. 20, 1967, Ser. No. 9,088

Term of patent 14 years

U.S. Cl. D15—11
Int. Cl. D6—01

FIG. 1.

FIG. 2.

FIG. 3.

The side not shown is a mirror image of the side shown while the back of the chair is conventional in configuration.

I claim:

The ornamental design for a chair, substantially as shown and described.
